UNITED STATES PATENT OFFICE.

WILLIAM M. GILBERT, THEODORE M. GILBERT, AND WILLIAM C. NASH, OF
NEENAH, WISCONSIN.

WIRE OR FELT GUIDE FOR PAPER-MAKING MACHINES.

SPECIFICATION forming part of Letters Patent No. 735,362, dated August 4, 1903.

Application filed June 1, 1903. Serial No. 159,449. (No model.)

To all whom it may concern:

Be it known that we, WILLIAM M. GILBERT, THEODORE M. GILBERT, and WILLIAM C. NASH, citizens of the United States, and residents of Neenah, in the county of Winnebago and State of Wisconsin, have invented a new and useful Improvement in Wire or Felt Guides of Paper-Making Machines, of which the following is a specification.

10 Our invention relates to mechanism for guiding the wires or felts upon their carrying-rolls on paper-making machines for causing them to run in their proper straight course and not to the right or left of said course; 15 and it consists of mechanism for producing said result by the revolutions of said carrying-rolls, as will be herein described.

Figure 1 is a plan view of a small section of each end of the wire or felt carrying roll 20 of a paper-making machine, the journal-bearings which support the same, and the mechanism for moving the left-hand end of said roll forward or backward. For want of room the right-hand end of the roll laps over the 25 base of the mechanism for moving the left-hand end of said roll. Fig. 2 is an elevation showing the rear side of the roll-sections shown in Fig. 1 and an end view of the stand upon which the mechanism for moving the 30 left-hand end of the roll forward or backward is mounted. Fig. 3 is a vertical section longitudinally of its shaft of a beveled-face pulley which enters into the construction of the mechanism. Fig. 4 is a front elevation of the mechanism for moving the left-hand end of the roll forward or backward and showing also the left-hand end of said roll. Fig. 5 is a transverse section of the 35 journal-box for supporting the left-hand journal of the roll as it appears in looking to the left of the line *a a* of Fig. 2. Fig. 6 is a side elevation of a ratchet-wheel, its side-inclosing ears, and the movable journal-box support for the left-hand end of the wire and felt carrying roll.

Similar characters indicate like parts in the several views.

1 indicates the bed-timbers of a paper-making machine; 2^a, the left and righthand ends, 50 respectively, of the wire or felt carrying roll, the journal-shaft 2^a of the left-hand end be-

ing supported in the journal-box 3, which is mounted to turn horizontally in its supporting-stand 4, and the journal-shaft 2^b of the right-hand end being arranged to turn in a like manner in its supporting-stand 4', 55 5 being a block under stand 4' for bringing the end of the roll to a corresponding height, and 4" being bolts for securing the stand 4' in position.

6 indicates the bed-piece of the stand 7, which stand is arranged to slide toward and from the end 2 of the roll, the stand being held in position upon the bed-piece and guided in its sliding movement by gibs 8^a, 65 the latter gib being detachable and provided with bolts 8" for adjusting its position upon the bed-piece. The bed-piece is provided with ears 6', by which the bed-piece may be secured upon the bed-timber 1.

7 is a screw arranged across the bed-piece, revoluble in the boss 10, which boss projects upward from the piece 6 between collars 11 11' on the screw, the screw engaging the nut 12 and being provided with a crank and 75 handle 13, by means of which the screw may be turned and the stand 7 moved transversely of the paper-machine.

The stand 7 consists of its base 14, ends 15 and 15', top piece 16, having the way 17, upon 80 which the journal-box stand 4 is arranged to slide within the groove 18, and a shelf 19, upon which the lower end of the stand 4 is supported and slides. The stand 4 is provided with ears 20, which depend upon each side 85 of the ratchet-wheel 21 in close connection with it and join together in the rear of said wheel. The wheel is internally threaded, provided with teeth 21^a, and mounted upon the screw 22, the screw being secured in a 90 fixed position in the ends of the stand 7, so that by turning the wheel upon the screw it is carried along toward one end or the other of the screw, and the supporting-stand 4 is moved along upon the way 17 and shelf 19, 95 and the end 2 of the roll thereby moved either in or opposed to the direction in which the wire or felt is running, said direction being indicated in these drawings by the arrow above, Fig. 4.

Upon the outer end of the journal-shaft 2^a a wheel 23 is mounted, it being provided with

a crank-pin 24, from which is suspended by the link 25 the dog-holder 26, said holder being connected at the point of the pin or screw 27 by means of the link 28 with a pin 29, 5 which extends out from the arm 30 of the supporting-stand 4, so that by means of said two links the dog-holder is pivotally supported and held at the point 27 and by means of the continuous action of the crank-pin at the end 10 of the shaft 2^a is made to reciprocate in a nearly vertical direction.

Below the point 27 the dog-holder branches to the right, 26", and left, 26', of the ratchet-wheel and is provided with enlargements 31 15 31' and dogs 32 32', which dogs are adjustably secured in said enlargements with set-screws 33, and above the point 27 the holder is curved for clearing the crank-pin and upper end of the link 25 and is then extended upward vertically, 26", and provided with a slot 34.

The left-hand end of the wire or felt carrying roll terminates at the dotted line 35, (see Figs. 1 and 2,) its shaft being enlarged over its journal diameter, as shown by dotted lines 25 36, so that the roll is held from endwise movement in its journal-box 3 between said enlarged portion and the wheel 23, and any movement of the stand 7 transversely of the paper-machine will carry the roll with it, the 30 right-hand-end journal-shaft being made sufficiently long, as shown, for allowing the necessary endwise movement for suiting the position of the roll to the running of the wire or felt.

35 Upon the left-hand end of the roll from the line 37 a band 38 of some suitable flexible material, as leather, is secured, it projecting over the end of the roll from the dotted line 35 to the end 38'. 39 indicates the wire or 40 felt in Figs. 2 and 4 over said band, they being omitted in other figures for clearness of illustration.

Supported upon the journal-box 3 by the bows 40 and mounted in suitable journal-boxes 41 within said bows is a shaft 42, having upon its inner end a beveled-face pulley 43 and upon its outer end a wheel 44, having a crank-pin 45 extending out from it and entering loosely into the slot 34 of the dog-holder. Mounted upon the shaft 42 is a collar 46, adjustably secured thereon by means of a set-screw 47, having one end of a coiled spring 48 secured to it, the spring being arranged around the shaft 42 and its other end 50 resting against the outside of the journal-box 3.

60 The pulley 43 is arranged at the end of the wire or felt carrying roll with its top surface bearing up under the flexible band, so that the outer end of said beveled-face pulley will raise said band higher than the top of the roll and form an incline from the end of the roll to the outer edge of the band, along which the edge of the wire or felt will travel whenever 65 it is inclined to run too far outward beyond the end of the roll. The wire or felt in running up this incline is caused by it to bear upon

the band and said band to bear upon the top surface of the beveled-face pulley and cause it to oscillate in the direction in which the wire or felt is running. The oscillation of the pulley will oscillate the wheel 44 and throw the crank-pin 45 against the right-hand side of the slot 34, and consequently swing the dog 32' into engagement with the teeth upon the right-hand side of the ratchet-wheel, Fig. 4, turning said wheel as the dog-holder is reciprocated and moving the journal-box 3 toward the left, and consequently changing the position of that end of the roll toward the left 80 and causing the wire or felt to run toward the end 2'.

For causing the wire or felt to run toward the beveled-face pulley the action of the spring 48 is relied on, the spring being coiled in the proper direction for oscillating the beveled-face pulley in an opposite direction from that in which the wire or felt is running. The crank-pin 45 is consequently thrown against the left-hand side of the slot 34, and thereby 90 swings the dog 32 into engagement with the left-hand side of the ratchet-wheel and turns it upon the screw 22, so as to move the journal-box 3 in opposite direction from that in which the wire or felt is running, and consequently causing said wire or felt to run toward the pulley 43.

The guide herein shown is one that is termed "a left-hand guide"—that is, one adapted for the left-hand side of the wire or felt as it is running from the observer. It can be adapted for the right-hand side by slight changes in its construction, such as extending the slot 34 farther upward and placing the crank-pin 45 above instead of below the center of the shaft 105 42, as shown in dotted lines in Fig. 2, coiling the spring 48 in the reverse direction and arranging the lower end of said spring upon the opposite side of the journal-box 3, as shown in dotted lines in Fig. 5.

110 In describing this invention a beveled-face pulley 43 is named as an element and is shown in the several figures; but it should be understood that a segment of a pulley 43', as is shown by heavy lines in Fig. 4, or the entire pulley, as is shown by both heavy and dotted lines in Fig. 4, is within the scope of our invention and is included in the term "beveled-face pulley." A small section of the upper part of the pulley is all that is required for throwing the dogs into engagement with the ratchet-wheel upon either side, but for reasons obvious to a mechanic in their manufacture and in their even running the entire pulley is preferable. The flexible extension or band 38 is also described as an element in the improvement; but its use is not required, for if the wire or felt is allowed to come in direct contact with the pulley 43 it will oscillate it as effectually as it would if the 125 wire or felt bore upon the band and said band then transferred said pressure to the pulley; but for lessening the wear upon the edge of the wire or felt the band extended

over the end of the roll is preferable, the slight difference in construction being that in using the band the top of the small end of the pulley is placed below the top of the roll 5 the thickness of said band, while in dispensing with it the tops of the pulley and roll should be flush with each other.

The upper end of the link 25 is provided with a slotted aperture 49 instead of a circular 10 bore for the purpose of the engagement therewith of the crank-pin 24, so as to prevent any liability of the binding of the pin by reason of the action of the two links which control the movements of the holder 26.

15 Attached to the end 15 of the stand 7 is a flexible connection 50, which extends to and is connected with the left-hand dog-holder for the purpose of limiting the movement of the dog-holder and journal-box 3 toward the 20 right beyond a predetermined limit for preventing injury to any of the parts.

Having described our invention, what we claim, and desire to secure by Letters Patent, is—

25 1. In a wire or felt guide for a paper-making machine, a guiding-roll for supporting and guiding said wire or felt, one end thereof being provided with a suitable bearing for supporting and for the revolution of said roll and having 30 an elongated journal-shaft upon which the roll can be moved endwise, the journal-shaft of the other end of said roll being mounted in a bearing which is adjustable in position in a line parallel with the normal 35 line of travel of said wire or felt, and also, transversely thereof, a suitable stand upon which the latter bearing is supported, a suitable base for supporting said stand and a screw and nut arranged for moving said stand 40 upon the base and thereby moving said roll lengthwise, substantially as described.

2. In a wire or felt guide for a paper-making machine having a screw suitably arranged and a ratchet-wheel provided with teeth upon opposite sides thereof mounted for revolution upon said screw, a dog-holder pivotally mounted and comprising two depending arms, each arm carrying a dog for engagement with the teeth upon one side of said wheel, and an arm 50 extending upward having a slot vertically arranged for the engagement therewith of a crank-pin suitably arranged and having an oscillating movement for oscillating said holder and engaging the teeth of one of its depending arms with those upon one side of said ratchet-wheel for turning the same, substantially as described.

3. In a wire or felt guide for a paper-making machine having a guiding-roll adapted for carrying said wire or felt, and a horizontally-adjustable bearing supporting one end of said roll, and having a suitable holder provided with dogs, said holder being arranged for a nearly-vertical movement and engaging the teeth of said dogs with the teeth upon a ratchet-wheel for producing said horizontal movement, a guiding mechanism for said wire or

felt comprising the guiding-roll, a beveled-face pulley arranged for oscillation upon one end of a shaft at the horizontally-movable end 70 of said roll, the top surface of the smaller end of said pulley being arranged to receive the pressure of the edge of said wire or felt whenever it runs over said end of its carrying-roll, a wheel upon the other end of said shaft, a 75 crank-pin extending out from said wheel and being arranged for engaging a slot near the upper end of the aforesaid dog-holder and oscillating the same for throwing the dog upon one side of the ratchet-wheel into engagement 80 with its teeth for turning said wheel and moving said movable end of the roll forward, and a spring arranged for oscillating said pulley in the reverse direction for moving said end of the roll backward, substantially as set forth. 85

4. In a wire or felt guide for a paper-making machine having a guiding-roll adapted for carrying said wire or felt, and a horizontally-adjustable bearing supporting one end of said roll, and having a suitable holder provided 90 with dogs arranged for a nearly-vertical movement for engaging teeth upon opposite sides of a ratchet-wheel and thereby turning said wheel and producing the horizontal movement to the aforesaid bearing, a guide for said wire 95 or felt, comprising the wire or felt carrying roll, a flexible band secured upon said movable end of the roll flush upon its outer surface with that of said roll and extending beyond the end of said roll, a beveled-face pulley arranged upon one end of a shaft for oscillation therewith at said end of the wire or felt carrying roll with its upper surface arranged to receive the pressure of the wire or felt whenever it runs over said end of the carrying-roll, a wheel upon the other end of said shaft, a crank-pin extending out from said wheel and being arranged for engaging a slot near the upper end of the aforesaid dog-holder and oscillating the same for throwing the dog 100 upon one side of said ratchet-wheel into engagement with its teeth for turning the same and moving said end of the roll forward, and a spring arranged for oscillating said pulley in the reverse direction for moving said end 105 of the roll backward, substantially as described.

5. The combination in a wire or felt guide for a paper-making machine of the following elements, a wire or felt carrying roll having 110 the journal-shafts 2^a and 2^b, the former having the wheel 23 and enlargement 36; the journal-boxes 3 and 3', the supporting-stands 4 and 4', the bed-piece 6, the stand 7 arranged to be moved transversely of the bed-piece, a 115 screw and nut arranged for making said movement, a screw arranged in the stand 7 transversely of said roll, the ratchet-wheel 21 having teeth 21' upon opposite sides thereof mounted for revolution upon said screw, the 120 ears 20 depending from the stand 4, between which ears said wheel revolves, the way 17 and shelf 19 for supporting and guiding the stand 4, the beveled-face pulley 43 mounted

upon the shaft 42 for oscillation above the journal-shaft 2^a at the end 2 of the roll, its top surface being at a height relative to said roll for receiving the pressure of the wire or 5
felt whenever its edge runs over said end of the roll, the wheel 44 upon the outer end of the shaft 42 having the crank-pin 45, the dog-holder 26, mounted for oscillation upon the pin 27 and having arms 26' 26'' and 26^a, the 10
latter arm having the slot 34 adapted to receive the crank-pin 45 for oscillating said dog-holder, engaging the dogs with the teeth of the wheel and thereby turning said wheel and moving the stand 4 forward in a line 15
parallel with the normal line of travel of said wire or felt, and a spring arranged for causing said dog-holder to be oscillated for turning said ratchet-wheel reversely and moving said stand in the opposite direction, substantially as set forth.

6. In a wire or felt guide for a paper-making machine having a guiding-roll for carry-

ing said wire or felt, one end of which roll is arranged for a horizontal movement in a line parallel with the normal line of travel of said 25
wire or felt by mechanism operated by the revolutions of said roll, a beveled-face pulley mounted upon one end of a shaft for oscillation, the top surface at the smaller end being arranged at a height for receiving the pressure thereon of the wire or felt whenever the edge thereof runs over said movable end of said roll and onto said surface, a wheel upon the opposite end of said shaft, and a crank-pin extending out therefrom for engaging 30
the aforesaid horizontally-moving mechanism, substantially as described.
